UNITED STATES PATENT OFFICE.

ALBERT EDWARDS, OF BROOKLYN, NEW YORK.

IRONING BOARD.

Application filed August 30, 1921. Serial No. 496,847.

To all whom it may concern:

Be it known that I, ALBERT EDWARDS, a citizen of the United States, and a resident of the borough of Brooklyn, in the city and State of New York, have invented certain new and useful Improvements in Ironing Boards, of which the following is a specification.

My invention relates to ironing boards, and particularly to means for securing a cover thereon and providing an iron-rest therefor, and has for one of its objects to provide such a board and such securing means which may be easily and cheaply made, of simple construction and convenient of manipulation, and which shall permit the iron-stand, while remaining secured to said board, to be used upon either side of the same as desired.

The invention consists in the novel construction, arrangement and combination of various elements and parts, as hereinafter set forth in the claim hereof, certain embodiments of the same being shown in the accompanying drawings and fully described in this specification.

In the accompanying drawings, Fig. 1 is a perspective view of an ironing board provided with a cover and showing the same secured by a device constructed according to my invention and showing also an iron-stand attached thereto, a portion of the cover being broken away; Fig. 2 is a longitudinal vertical section along the line 2—2 of Fig. 1; Fig. 3 is a view on an enlarged scale of a part of the cover-securing device; and Fig. 4 is a view of a modified form hereinafter more particularly described.

In carrying my invention into effect in the embodiments thereof which I have selected for description in this specification and illustration in the accompanying drawings, I provide an ironing board of the usual or any suitable size and shape, the same being designated by the reference numeral 5, and in the end thereof I provide a kerf or groove 6. The board may be provided on one or both sides with a soft layer of material or cushion of approximately the same size and shape, shown at 7 in the drawings, and over all is slipped a cover 8. Ironing boards are usually somewhat smaller at one end than at the other, and the outer cover which is intended to be slipped over the board is of a corre-

sponding shape, and open at one end in a manner which is well understood, and my invention contemplates the preferred use of a board and cover of such shape and mutual adaptation; the cover is, however, provided with flaps at its open end long enough to permit of the same being turned backwards and inwards and inserted into the groove 6.

A preferred form of securing means is shown at 9 in Fig. 1, and a portion of the same on an enlarged scale in Fig. 3. This device as shown in the drawings is formed of a wire, or a strip of metal, large enough when inserted in the groove 6 to bind therein and to hold the inturned flaps of the cover securely in place. The wire 9 is preferably bent into an undulating shape as shown best in Fig. 3, two of the upwardly extending loops, however, designated 10, being squared and extending outward beyond the others when the wire is inserted into the groove 6.

Devices for securing the iron-stand to the board are shown in Figs. 1 and 2 and designated 11. These devices consist, as shown, of loops of sheet metal, but may of course be composed simply of wire. They are placed upon the squared loops 10 of the securing device and are of approximately sufficient length to extend from the middle of the board to somewhat beyond either of the side surfaces, as shown in Fig. 1, and the outer ends of these loops serve for the reception of the ends of an iron-rest 12, which, as is shown in Figs. 1 and 2, is formed of a wire or strip of suitable material bent into an undulating form and adapted to receive an iron when not in use.

In Fig. 4 I show a modification of my invention which comprises a cap 13 which is adapted to be placed over the end of the board after the cover has been placed upon the same, the edges inturned, and a securing device such as 9 inserted. This cap 13 may be used in case it is desired not to have the open groove in the end of the board disclosed to sight. To the cap 13 are attached a pair of staples 14, which are adapted to hold loops 11 in the same manner as does the securing device 9, to which loops an iron-rest 12 may be secured as already referred to and as indicated in Figs. 1 and 2 of the drawings.

The operation or method of use of my invention will be obvious from the drawings

and from what has been above said with regard to the construction of the device.

The advantages of my invention will be obvious. I might particularly mention the 5 ease with which a cover may be placed upon the ironing board and secured thereto in perfect smoothness, and if any wrinkle should appear in the cover, it is easy to loosen the securing device 9, smooth out the 10 wrinkle, and resecure the cover. No tacks or similar devices are necessary, owing to the close fitting of the cover to the board as has been pointed out, the securing device tightening the cover in a manner analogous 15 to the tightening of a drum-head. By using the above described iron-rest and securing the same to the board, there is no danger of losing the rest, and the same is always at hand for use when desired, and yet, as will 20 be evident, the rest can be used with equal facility on either side of the board. If it is desired, however, to remove the rest from the board, this can easily be done by slipping the ends of the same out from the loops 25 11, as will be readily seen from Fig. 1.

I do not limit myself to the exact forms of the invention shown and described, as it is obvious that various changes might be made without departing from the spirit and scope of my invention. For instance, instead of 30 using a securing device of the form shown in Fig. 3 of the drawings, I may employ any equivalent means adequate for the required purpose.

Having thus described my invention, 35 what I claim as new and desire to secure by Letters Patent is as follows:

The combination with an ironing board provided with a slot in the edge thereof, and a cover adapted to be placed over said board 40 having a portion thereof projecting beyond the edge of the board and adapted to be inserted in said slot, of a securing device adapted to be placed in said slot and to secure therein a portion of said cover, an iron-rest, and devices adapted to swingingly connect said iron-rest to said securing device. 45

Signed at New York city, N. Y., this 16th day of August, 1921.

ALBERT EDWARDS.
